UNITED STATES PATENT OFFICE.

ADAM GRISSE, OF NORTH WEBSTER, INDIANA.

HAME-TUG.

SPECIFICATION forming part of Letters Patent No. 639,230, dated December 19, 1899.

Application filed March 29, 1899. Serial No. 710,982. (No model.)

To all whom it may concern:

Be it known that I, ADAM GRISSE, a citizen of the United States, residing at North Webster, in the county of Kosciusko and State of Indiana, have invented new and useful Improvements in Hame-Tugs, of which the following is a specification.

This invention relates to improvements in adjustable metallic hame-tugs, and the novelty and many advantages will appear from the following description and claims when taken in connection with the annexed drawings, in which—

Figure 1 is a plan view of my improved tug with a part of a trace attached thereto and the hame-attaching plate partly broken away. Fig. 2 is a sectional view taken in the plane indicated by the dotted line $x-x$ on Fig. 1. Fig. 3 is a perspective view of one of the sections of the tug. Fig. 4 is a perspective view of one end of the trace. Fig. 5 is a perspective view of the buckle-plate. Fig. 6 is a perspective view of the trace guiding and retaining loop, and Fig. 7 is a perspective view of what I shall call a "loop" for slip-loop harness.

Referring by letter to said drawings, A indicates my improved metallic tug. This tug is made up of a suitable number of sections hinged together and each adapted to receive a trace end, so that the trace may be lengthened or shortened, and the tug itself may be lengthened or shortened by supplying sections or removing sections, as the case may require. Each section of this metallic tug is of a general rectangular elongated form in outline, having a central longitudinally-disposed slot a , and at the rear end of said slot a forwardly and inwardly directed or angular hook b , for a purpose which will presently appear. These hooks, which extend from the rear cross-wall of the slot, have their inwardly-directed ends terminating about flush with the inner sides of the sections, or approximately so, and are rounded on their outer sides, as shown. Each section is furthermore constructed with a reduced extension c at the hook end, and these extensions have a transverse hole d to receive a pintle, and at the opposite end are provided two lateral longitudinally-disposed branches e , formed by a recess f , and these branches have aligned holes

g to receive the cross-pin or pintle h . It will thus be seen that by bringing the reduced extension having the transverse hole in the end of one section into the recess f of the contiguous end of another section, so that the apertures or holes register, the pintles h may be inserted so as to form a hinged joint. Should it be desirable to shorten the tug, any one or more of the sections may be removed by withdrawing the pins or pintles at the joints and the remaining sections coupled up, as before.

B indicates the hame-attaching plate. This plate is provided at one end with a reduced extension and a hole similar to the extensions on the sections C, and the opposite or forward end of this plate may be secured to the hame in any suitable manner.

D indicates a buckle-plate which is provided with an upwardly-directed loop i and a downwardly-directed loop j to receive such straps as are employed for taking over the back and under the belly. This plate is usually longer than the hinged sections of the tug and is provided at its forward end with pierced branches similar to those of the other sections to be connected therewith in a hinged manner, and it is provided at its opposite end with a rearwardly-directed loop k for the detachable connection of a trace guide-loop E. This loop k is of oblong form, its greatest width being in a transverse plane. The trace-loop E, as better shown in Fig. 6 of the drawings, is of a general rectangular form, having a T or cross head on its inner side for the attachment of the same to the buckle-plate, this T or cross head F being turned so that its narrowest portion will correspond with that of the loop or slot k in the plate D, when it will enter the same, and by then giving it a quarter-turn in either direction it will assume the position shown in Fig. 2 to receive the trace.

G indicates the trace, which may be of the construction usually employed, and may be made up of the two layers of leather, as shown. On the end of the trace, at the forward end thereof, I provide a hook H, which has its shank perforated and placed between the two layers of leather and there secured by means of rivets l , which take through an outer plate m , and which plate after being turned over the forward ends of the trace-

leathers is provided with a slot *n* for the passage of the shank of the hook *H*. The hook *H* is of angular form, and its inwardly-directed end *p* has a round hole *q* to receive the hooks *b* in the sections *C*. The width of this hook *H* should be but slightly less than the width of the slots *a*, so that it may move snugly therein, and there will be no liability of the hook on the trace or the eye thereof 5 turning off of the hook on the tug-section. To disconnect the trace from the hooks of the tug, it is first necessary to move the trace at right angles, or approximately so, to the tug and then slide the two in opposite directions, 10 the operation being the reverse to disconnect the parts. The trace is first passed through the guide-loop *E*, after the same has been attached to the buckle-plate, so as to prevent the trace from moving away from said plate 15 or tending to get into the rectangular position described, and when the forward end of the trace has been hooked to the tug this will avoid any tendency of the guide-loop *E* turning and disconnecting itself from the buckle-plate, while after the hooked end of the trace 20 has been disengaged from the hook of the tug the trace can, when desired, be entirely disconnected from the tug by simply turning the guide-loop *E* so that its cross-head *F* may 25 be withdrawn from the slot or loop *k* of the plate *D*.

In some cases it is desirable to have a very short tug—for instance, on what is known as “slip-loop harness”—and in such cases the 30 plate *D* may be removed and a plate *I* substituted. This plate *I* has one end constructed precisely the same as one end of the plate *D* and is provided at its opposite or rear end 35

with a laterally-directed loop *E'* for the purpose of receiving the trace and serving substantially the same purpose as the loop *E*. 40

Having thus described my invention, what I claim is—

1. A flexible, metallic hame-tug composed of sections connected in a hinged manner 45 and each having a slot and a forwardly and inwardly directed, angular hook in the slot; in combination with a trace having a forwardly and inwardly directed, angular hook at one end provided in its inwardly-directed 50 portion with an eye to receive the hooks of the hame-tug sections, substantially as specified.

2. A flexible, metallic hame-tug composed of sections connected in a hinged manner 55 and each having a slot and a forwardly and inwardly directed angular hook in the slot, and the buckle-plate *D* connected to one end of the tug and having the upwardly and downwardly directed loops and also having a 60 loop at its rear end; in combination with a trace having a forwardly and inwardly directed angular hook at its forward end provided in its inwardly-directed portion with an eye to receive the hooks of the hame-tug sections, and the loop receiving the trace and 65 having the T-head adapted to be detachably secured in the rear loop of the buckle-plate *B*, substantially as specified.

In testimony whereof I have hereunto set 70 my hand in presence of two subscribing witnesses.

ADAM GRISSO.
